ERNST HÄNNI, OF ARBON, AND HANS STAMM, OF ST. GALLEN, SWITZERLAND,
ASSIGNORS TO FIRMA ADOLPHE SAURER, OF ARBON, SWITZERLAND, A
FIRM OF SWITZERLAND.

AUTOMATIC RIFLE.

1,346,494.

Specification of Letters Patent. Patented July 13, 1920.

Application filed February 27, 1918. Serial No. 219,512.

To all whom it may concern:

Be it known that we, ERNST HÄNNI, a citizen of the Republic of Switzerland, residing at Arbon, Switzerland, and HANS STAMM, a citizen of the Republic of Switzerland, residing at St. Gallen, Switzerland, have invented certain new and useful Improvements in Automatic Rifles; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to automatic rifles provided with a sliding barrel. In such rifles it frequently occurs, that when the rifle is ready to be fired, *i. e.* when the barrel should be in its foremost position and the closing spring for the barrel or breech action is nearly wholly untensioned, the barrel or the breech action or both are moved somewhat backward in consequence of a manipulation causing, for instance, the rifle to knock against the ground, and partly also in consequence of their gravity. When the striker is cocked, the striking spring is also able to pull the barrel and the breech action slightly backward. The result of such a rearward movement is, that the rifle misses fire.

To remedy this drawback, it has already been proposed to provide devices for locking the sliding barrel of rifles ready to be fired. These known devices, however, release the barrel too early on actuation of the trigger, the releasing being effected while the striker is still cocked, so that notwithstanding the provision of such devices the barrel may be still moved backward before a shot has been fired.

According to the present invention, this drawback is to be remedied by providing on an automatic rifle with a sliding barrel a device for locking the barrel while the striker is cocked, which is automatically released immediately after that the releasing of the striker is effected and before the latter strikes against the cartridge, *i. e.* before a shot is fired.

Two forms of construction of the invention are shown by way of example in the accompanying drawings.

55

In these drawings:

Figure 1 is a side view, partly in section, of the first embodiment, illustrating the device for locking the barrel in the operative position.

60

Fig. 2 is a corresponding view, showing the parts of the locking mechanism in the position, which they assume immediately before the releasing of the barrel.

Fig. 3 is a bottom view corresponding to Fig. 1.

Fig. 4 is a section on the line IV—IV of Fig. 1.

Fig. 5 is a side view, partly in section, of the second embodiment illustrating the locking mechanism in its operative position.

70

Fig. 6 is a vertical longitudinal section through a part of this embodiment, showing the locking mechanism in a position, in which the barrel is unlocked.

75

Fig. 7 illustrates a detail and

Fig. 8 is a cross-section on the line VIII—VIII of Fig. 5.

In the first embodiment shown, 1 denotes the barrel and 2 the breech frame. 3 is a guiding lug provided on one side of the breech frame 2 and adapted to slide in a groove 4 of a casing 5. The breech frame 2 forming an extension rigidly connected with the barrel 1 enters into the casing 5 when the barrel 1 is moved rearward. 6 denotes a sear provided with a lug 7. This sear is acted upon by a spring 8 and by a pawl 10 pivotally mounted on the trigger 9. The latter is pivotally carried by a lever 22 adapted to pivot about a bolt 12 and acted upon by a spring 13. The bolt 12 is mounted in the casing 5. 11 is the striker provided with a lug 14 adapted to coöperate with the lug 7 of the sear 6.

85

In this first embodiment, the underside of the casing 5 is provided with two extensions 15, 16. In the extension 15 is pivotally mounted a locking lever 17 and in the extension 16 a pressure member 18 acting upon the locking lever 17. The locking lever 17 has an end surface 19, which in the foremost position of the barrel 1 rests on a surface 20 of the guiding lug 3. 21 is a

90

95

100

spring acting upon one end of the locking lever 17. One end of the pressure member 18 acts from beneath upon that end of the locking lever 17, which is acted upon by 5 spring 21, while the other end of this member 18 rests on a lug 23 provided on the lever 22.

When the barrel is in its foremost position and the striker 11 is cocked, *i. e.* before a 10 shot is fired (see Fig. 1), the surface 19 rests on the surface 20, so that the barrel, together with the breech frame and the breech action adapted to be rigidly connected to said frame, are locked in this position. Any engagement of the lever 17 with a part of the breech frame or breech action results in such a locking of the barrel. When the trigger 9 is pulled backward for the 15 purpose of firing a shot, lug 23 presses upon the member 18 and the latter presses then upon the locking lever 17. In consequence of this, the lever 17 is moved in such a manner, that its locking surface 19 is caused to disengage the surface 20, so that the barrel 20 together with the breech frame 2 and the breech action are released. They are now able to effect a longitudinal displacement. Owing to said pulling on the trigger 9, the 25 sear 6 is pressed downward simultaneously with said releasing movement, and upon the surpassing of the so-called pressure point, the striker 11 is released.

The arrangement is thereby such, that the releasing of the barrel, and therefore also 30 of the breech frame and the breech action rigidly connected thereto, by the lever 17 is effected immediately after the releasing of the striker 11 and before the latter strikes against the cartridge (Fig. 2 shows the parts 35 in the position immediately before the barrel is released). On the releasing of the trigger 9, the spring 21 causes the locking lever 17 and the pressure member 18 to return into their original position, so that the barrel 40 and the breech action, which are already moved into their foremost position before the trigger 9 is released, are again automatically locked.

In the second embodiment of the invention, a fork-shaped lever 24 is pivotally mounted on the same bolt on which is pivotally mounted the sear 6. The lever 24 stands, in the same manner as the sear 6, under the pressure of springs 25 and it is 50 provided with two lugs 26, 27. Lug 27 cooperates with a projection 28 of the breech action 29. The lug 26 is provided with an inclined surface and projects with a knife-edge in the direction of the front aperture 55 of the barrel. The breech frame 2 is provided on its underside with a lug 30 having an inclined surface and a knife-edge projecting rearward.

In the foremost position of the barrel, the 60 knife-edge of the lug 26 comes behind the

knife-edge of the lug 30, so that the barrel, together with the breech action, is locked in this position. In this position, the lug 14 of the striker presses against the lug 7 of the sear 6, so that the rifle is ready for 70 firing (Fig. 5). On the pulling on the trigger 9, for the purpose of firing a shot, the pawl 10 presses the sear 6 and the lever 24 downward, so that the lugs 7 and 26 disengage the lugs 14 and 30 respectively. The 75 striker 11 is then released and the barrel is unlocked, so that it can be displaced longitudinally, said unlocking being effected also in this embodiment immediately after the releasing of the striker and before the latter strikes against the cartridge. During the forward sliding movement of the barrel and of the breech frame taking place after that a shot has been fired, the inclined surface of the lug 30 cooperates with the inclined surface of the lug 26, so that the lug 30 causes the lever 24 to move downward. In consequence of this, the breech action 29, which during the forward movement of the barrel was at first held back owing to the 80 engagement of the projection 28 with the lug 27, is now released and at the moment, at which the barrel reaches its end position the knife-edge of the lug 26 is immediately 85 caused to engage behind the knife-edge of the lugs 30, so that the barrel is again 90 locked against any longitudinal movement.

According to this invention the barrel, and therefore also the breech action, is automatically locked and the releasing of the 100 barrel is effected by the actuation of the trigger. No special manipulations are therefore required for locking or releasing the barrel and the breech action, so that the handling of the fire-arm is not rendered more difficult 105 owing to the provision of the locking mechanism.

It will be seen, that in the two embodiments shown the device according to the invention effects directly a locking of the 110 rigid integral piece formed by the barrel and the breech frame.

What we claim as our invention is:

1. In an automatic rifle, a sliding barrel, a breech frame connected rigidly with the 115 barrel, a breech action adapted to be rigidly connected to the breech frame, a striker mounted in the breech action, a casing into which the sliding barrel, together with the breech frame, is adapted to enter, means for retaining the striker in cocked position, means for locking the barrel when the 120 striker is cocked, a trigger carried by the casing and means operatively connected to such trigger and operated thereby for releasing the striker and releasing the barrel immediately after a releasing of the striker and before the striker strikes against the cartridge.

2. In an automatic rifle, a sliding barrel, a 125

breech frame provided with a lug and connected rigidly with the barrel, a breech action adapted to be rigidly connected to the breech frame, a striker mounted in the breech action, a casing into which the sliding barrel, together with the breech frame, is adapted to enter, means mounted on the casing for retaining the striker in cocked position, means also mounted on the casing 10 adapted to engage the lug on the breech frame for the purpose of locking the latter, and therefore also the barrel rigidly connected thereto, when the striker is cocked, a trigger carried by the casing, and means 15 operatively connected to such trigger and operated thereby for releasing the striker and releasing the barrel automatically immediately after a releasing of the striker and before the striker strikes against the cartridge.

3. In an automatic rifle, a sliding barrel, a breech frame provided with a lug and connected rigidly with the barrel, a breech action adapted to be rigidly connected to the breech frame, a striker mounted in the breech action, a casing into which the sliding barrel, together with the breech frame, is adapted to enter, means mounted on the casing for cocking the striker, a lever pivotally mounted on the casing and provided 25 with a lug, springs acting upon the lever for the purpose of bringing its lug behind the lug of the breech frame in order to lock the latter, and therefore also the barrel rigidly connected thereto, when the striker is cocked, a trigger carried by the casing, and means 30 operatively connected with the trigger and with the means for cocking the striker and the spring pressed lever to release the striker 40 and the barrel immediately after the striker

is released and before the striker strikes against the cartridge.

4. In an automatic rifle, a sliding barrel, a breech frame provided with a lug on its rearward end and forming an extension 45 rigidly connected with the barrel, a breech action adapted to be rigidly connected to the breech frame, a striker mounted in the breech action and provided with a lug, a casing into which the sliding barrel, together 50 with the breech frame, is adapted to enter, a sear pivotally mounted on the casing and adapted to engage the lug of the striker for the purpose of cocking the latter, a spring pressing on the sear, a lever also 55 pivotally mounted on the casing and provided with two lugs, one of the latter being adapted to coöperate with the lug of the breech frame for the purpose of locking the frame, and therefore also the barrel, 60 when the striker is cocked, while the other one of said lugs is adapted to lock the breech action at the beginning of forward sliding movement of the barrel until it is caused to release the breech action under the 65 influence of the lug on the breech frame acting upon the other lug of the lever, springs acting on this lever and a trigger carried by the casing, the trigger being adapted to act in such a manner upon the sear and the 70 lever, that the barrel is automatically released by the lever immediately after a releasing of the striker caused by a pulling on the trigger, and before the striker strikes against the cartridge.

In testimony that we claim the foregoing as our invention, we have signed our names.

ERNST HÄNNI.
HANS STAMM.
